CLARENCE A. BODDIE, OF PITTSBURGH, PENNSYLVANIA, ASSIGNOR TO WESTINGHOUSE ELECTRIC & MANUFACTURING COMPANY, A CORPORATION OF PENNSYLVANIA.

FURNACE-REGULATOR SYSTEM.

Application filed August 26, 1919. Serial No. 319,906.

To all whom it may concern:

Be it known that I, CLARENCE A. BODDIE, a citizen of the United States, and a resident of Pittsburgh, in the county of Allegheny and State of Pennsylvania, have invented a new and useful Improvement in Furnace-Regulator Systems, of which the following is a specification.

My invention relates to regulator systems 10 and particularly to regulator systems for governing the operation of the movable electrodes in electric furnaces.

One object of my invention is to provide a furnace-regulator system that shall operate 15 the movable electrodes in an efficient manner to maintain constant current flow through them and that shall be free from so-called hunting action.

In operating electric furnaces of the movable-electrode type, it is customary to raise 20 and lower each electrode, relative to the bath of material being treated, by means of an electric motor and to govern the operation of the motor in accordance with the current flowing through the electrode associated 25 with it. Such means for regulating the operation of a furnace is fairly satisfactory under normal operating conditions but it is difficult to obtain satisfactory or 30 close regulation unless some means is provided to prevent the so-called hunting action.

In a furnace-regulator system constructed 35 in accordance with my invention, each movable electrode is operated in accordance with the current flowing through it and means is provided for preventing overtravel of the various parts of the regulator associated with each electrode and, accordingly, 40 for preventing so-called hunting action.

In practicing my invention, each movable electrode is provided with an electrode motor for raising and lowering it and a main control element which is governed in accordance 45 with the current flowing through the associated electrode, is provided for governing the operation of the electrode motor. The main control element associated with each electrode comprises a main magnet which is 50 energized in accordance with the current flowing through the electrode and an auxiliary magnet which is operated by the main magnet to prevent hunting action. The main magnet selectively operates two switches for

rotating the electrode motor in a clockwise 55 or in a counterclockwise direction to maintain a constant current flow through the electrode. The auxiliary magnet is mechanically connected to the main magnet, herein shown to be by a fluid connection, but 60 any other energy transmission connection may be used and is provided with a resistor in its energizing circuit which is varied by the switches to vary the operation of the auxiliary magnet to react on the main 65 magnet, and prevent hunting action. Thus, upon operation of the main magnet, one of the switches changes the energization of the auxiliary magnet which, in turn, changes the setting of the main magnet in a manner 70 to prevent overtravel and the so-called hunting action.

The single figure of the accompanying drawing is a diagrammatic view of a regulator system embodying my invention. 75

Referring to the drawing, an electric furnace 1, embodying a receptacle 2 containing a bath of material 3 and three movable electrodes 4, 5 and 6, is directly connected to a three-phase supply circuit comprising 80 conductors 7, 8 and 9.

Each of the movable electrodes is controlled by a regulator in accordance with the current flowing through the electrode and, inasmuch as these regulators are similar in construction and operation, only one regulator, namely, the regulator associated with the electrode 4, will be described in detail.

A motor 10, comprising an armature 11 90 and a field winding 12, is provided for raising and lowering the electrode 4. The field winding 12 is directly connected across a supply circuit comprising conductors 33 and 34. In the system shown in the drawing, the motor 10 is connected to the electrode 4 by means of a winding drum 13 and a flexible connector 14 which passes over a pulley 15 but it is to be understood that any other suitable connection may be provided for operating the electrode 4 by means of the motor. 100

A regulator, comprising a main control element 16 and two switches 17 and 18, is provided for governing the operation of the motor 10 to maintain constant current flow through the electrode 4. The main control element 16 embodies a main magnet 19 and

and auxiliary magnet 20. The main magnet 19 comprises a winding 21 which is connected to the three-phase supply conductor 9 by means of a current transformer 22. A 5 resistor 60 is connected across a winding 21 for varying the current supplied to the current transformer 22. A core armature 23, which is controlled by the winding 21, is directly connected to a contact arm 24 10 and is provided with a piston 25 which operates within a cylinder 26 for a purpose to be hereinafter set forth. The contact arm 24 is fulcrumed at 27 and carries a main contact member 28 which engages contact members 29 and 30, according to the operative position of the main electro-magnet 19.

The auxiliary electromagnet 20 comprises a winding 31 which is connected, in series 20 with the variable resistor 32, across the auxiliary supply circuit comprising conductors 33 and 34. The winding 31 operates the core armature 35, which is supported by a spring member 36 and is provided with a piston 37 25 which operates within a cylinder 38. The cylinder 26, which is associated with the electromagnet 19, and the cylinder 38, which is associated with the electromagnet 20, are connected by a pipe 40 containing any suitable fluid, preferably oil, in order that any 30 movement or action of the auxiliary electromagnet 20 may be transmitted to cause a corresponding effect upon the main magnet 19.

35 The switch 17 comprises a winding 41, which is connected across the supply conductors 33 and 34 upon engagement between the main contact members 28 and 29, and a core armature 42. The core armature 42 operates two switch members 43 and 44 and two interlock switch members 45 and 46. The two switch members 43 and 44 serve to connect the armature 11 of the motor 10 across the supply conductors 33 and 34 to 40 effect rotation of the motor in a clockwise direction to raise the electrode 4 from the bath of material 3. The interlock switch member 45 serves to short-circuit a portion of the resistor 32 which is included between 45 taps 47 and 48 when the switch 17 is operated in order to increase the energization of the auxiliary magnet 20 and to prevent so-called hunting action.

50 The switch 18 comprises a winding 49, which is connected across the supply conductors 33 and 34 upon engagement between the main contact members 28 and 30, and a core armature 50. The core armature 50 operates two switch members 51 and 52 and 55 two interlock switch members 53 and 54. The two switch members 51 and 52 serve to connect the armature 11 of the motor 10 across the supply conductors 33 and 34 in order to effect counterclockwise rotation of the motor to lower the electrode 4 in the fur-

nace 1. The interlock switch 53, upon operation of the switch 18, serves to open a short-circuit which normally exists across that portion of the resistor 32 which is included between the taps 48 and 55. The opening of 70 such short-circuit across a portion of the resistor 32 decreases the energization of the auxiliary electromagnet 20 to prevent hunting action when the electrode 4 is being lowered into the furnace. The interlock switch 75 members 46 and 54 serve to connect a braking relay 56 across the supply conductors 33 and 34 upon the simultaneous release of the switches 17 and 18. The relay 56, upon operation by the interlock switch members 46 80 and 54, completes a dynamic-braking circuit through a resistor 57 in order to effect a quick stopping of the motor 10.

In case a current above normal value flows 85 through the electrode 4, the energization of the main magnet 19 is increased to operate the contact arm 24 and to effect engagement between the contact members 28 and 29. Upon engagement between the contact members 28 and 29, a circuit is completed through 90 the winding 41 of the switch 17 to effect operation of the switch members 43 and 44. The switch members 43 and 44 connect the armature 11 across the supply conductors 33 95 and 34 and rotate the motor 10 in a clockwise direction to raise the electrode 4 from the bath of material 3.

If the motor 10 were controlled solely by 100 the effect upon the main magnet 19 of the current flowing through the electrode 4, the contact arm 24 would not be moved to separate the contact members 28 and 29 until normal conditions obtained in the circuit connected to the electrode 4. Consequently, 105 by reason of the inertia of the various moving parts of the regulator, it is apparent that the motor 10 would overtravel to raise the electrode 4 beyond the desired point and, accordingly, decrease the current flow through 110 it below normal value. In order to prevent such operation, the operation of the auxiliary magnet 20 is varied to effect separation of the same contact members just prior to the obtaining of normal conditions in the 115 electrode circuit.

Upon operation of the switch 17, the interlock switch member 45 short-circuits a portion of the resistor 32 and, accordingly, 120 increases the energization of the auxiliary magnet 20. The increased energization of the auxiliary magnet 20 tends to raise the core armature 35. The core armature 35, by means of the fluid connection between the two electromagnets, reduces the pressure upon the piston 25 which is connected to the core armature of the magnet 19. Accordingly, 125 the setting of the main magnet 19 is changed and the contact members 28 and 29 are separated just prior to the obtaining of normal current flow through the electrode 4.

- In case a current below normal value flows through the electrode 4, the energization of the main magnet 19 is reduced to effect engagement between the contact members 28 and 30. Upon engagement between the contact members 28 and 30, a circuit is completed through the winding 49 of the switch 18 for operating the switch members 51 and 52. The switch members 51 and 52 connect the armature 11 of the motor 10 across the supply conductors 33 and 34 to effect rotation of the motor in a counter-clockwise direction and, accordingly, to lower the electrode 4 in the furnace 1.
- Upon operation of the switch 18, the interlock switch member 53 opens the short-circuit which normally exists across a portion of the resistor 32 in order to decrease the energization of the auxiliary magnet 20.
- Upon decreasing the strength of the electromagnet 20, the pressure exerted on the piston 25 of the magnet 19, through the fluid connection, is decreased and, accordingly, the setting of the magnet 19 is changed so that a separation of the main contact members 28 and 30 is effected just prior to the obtaining of normal conditions in the electrode circuit.
- Thus, the main magnet 19 operates the switches 17 and 18 to control the motor 10 and raise and lower the electrode 4 to maintain a constant current flow through such electrode. The switches 17 and 18 also operate the resistor 32 to vary the energization of the auxiliary magnet 20 to change the setting of the main magnet 19 and prevent hunting action by the regulator.
- In the claims, where the terms "energy transmission connection" or "mechanical connection" are used, it is to be understood that any non-electrical connection is comprehended that will permit the electromagnets to function as herein described.
- In my copending application, Serial No. 342,175, filed December 3, 1919, I have illustrated, described and claimed a furnace-regulator system having other means for preventing hunting action.
- Modifications in the system and arrangement and location of parts may be made within the spirit and scope of my invention and such modifications are intended to be covered by the appended claims.
- I claim as my invention:
1. In a furnace-regulator system, the combination with a movable electrode and a motor for operating the electrode, of a main control element having a main electromagnet and an auxiliary electromagnet for operating said motor to maintain constant current flow through said electrode, and a fluid connection between the main magnet and the auxiliary magnet for controlling one magnet by the other magnet to prevent hunting action.
  2. In a furnace-regulator system, the combination comprising a movable electrode, means comprising a main control element for governing the operation of said electrode, said element comprising a main magnet operated in accordance with the current flowing through the electrode and an auxiliary magnet having a fluid connection with the main magnet, and means for varying the energization of the auxiliary magnet to operate the main magnet and prevent hunting action. 70
  3. In a furnace-regulator system, the combination with a movable electrode, and a motor for raising and lowering said electrode, of a main magnet operated in accordance with the current flowing through the furnace, means comprising contact members controlled by said main magnet for governing the motor to maintain a constant current flow through the electrode and an auxiliary magnet having a mechanical connection to the main magnet for operating it to prevent hunting action. 80
  4. In a furnace-regulator system, the combination with a movable electrode, of a main magnet operated in accordance with the current flowing through the electrode, two switches selectively operated by said main magnet for controlling said motor, an auxiliary magnet having a mechanical connection to said main magnet, and means controlled by said switches for varying the energization of the auxiliary magnet to operate the main magnet and prevent hunting action. 90
  5. In a furnace-regulator system, a movable electrode, means for raising and lowering said electrode, a main magnet for controlling the operation of said means to maintain a constant current flow through the electrode, an auxiliary magnet controlled by the main magnet and adapted to react on the main magnet to prevent hunting action. 105
  6. In a furnace-regulator system, a movable electrode, means comprising a main electromagnet for operating the electrode to maintain a constant current flow through it, and an auxiliary magnet controlled by the main magnet and reacting on the main magnet to prevent any hunting action. 110
  7. In a furnace-regulator system, the combination comprising a movable electrode, means comprising a main magnet for operating the electrode to maintain a constant current flow through it, an auxiliary magnet having a variable resistor in circuit with it, means for varying said resistor in accordance with the operation of the main magnet, and a mechanical connection between said magnets for governing the main magnet in accordance with the operation of the auxiliary magnet to prevent hunting action. 120
  8. In a regulator system, the combination comprising a supply circuit, a resistance- 130

varying member in said circuit, means comprising a main magnet for operating said member to maintain a constant current flow through said circuit, an auxiliary magnet connected in circuit with a variable resistance, means for varying said resistor in accordance with the operation of the main magnet, and a mechanical connection between said magnets for governing the main magnet in accordance with the operation of the auxiliary magnet to prevent hunting action.

9. In a furnace-regulator system, the combination comprising a plurality of movable electrodes, and regulators respectively associated with the electrodes for maintaining a constant current flow through the electrodes, each of said regulators comprising a main magnet operated in accordance with the current flowing through the associated electrode, a motor controlled by the main magnet for raising and lowering the electrode, an auxiliary magnet controlled by the main magnet, and a mechanical connection between said magnets for governing the main magnet in accordance with the operation of the auxiliary magnet to prevent hunting action.

10. In a furnace-regulator system, a movable electrode, means comprising a main electromagnet for operating said electrode in accordance with the electrode circuit conditions, and an auxiliary magnet for reacting on the main magnet to change its setting.

11. In a regulator system, the combination with a supply circuit, a motor, and a control magnet operated in accordance with the current flowing through the supply circuit, of means controlled by said magnet for operating the motor in a forward and in a reverse direction and for establishing a braking circuit through the motor, and means for preventing hunting action in said system.

12. In a regulator system, the combination with a supply circuit, a resistance-varying member associated therewith, and means for operating said member, of regulator mechanism therefor comprising an electromagnet operated in accordance with the current in said circuit, a second electromagnet and energy-transmitting mechanism co-operating with said second electromagnet and being adapted to react on said regulator mechanism to prevent hunting action in said system.

13. In a regulator system, the combination with a supply circuit, a resistance-vary-

ing member associated therewith, and means for operating said member, of regulator mechanism therefor controlled in accordance with the current in said circuit comprising a plurality of electromagnets and energy-transmitting mechanism connecting said electromagnets, one of which is adapted to act upon said regulator mechanism to prevent hunting action in said system.

14. In a regulator system, the combination with a supply circuit, a resistance-varying member associated therewith, and means for operating said member, of regulator mechanism therefor controlled in accordance with the electrical characteristics of said circuit and comprising a main electromagnet and a reactive electromagnet adapted to control said regulator mechanism so as to prevent hunting action in said system.

15. In a regulator system, the combination with a supply circuit, a resistance-varying member associated therewith, and means for operating said member, of regulator mechanism therefor comprising a main electromagnet and a reactive electromagnet adapted to govern the operation of said regulator mechanism so as to prevent hunting action in said system.

16. In a regulator system, the combination with a supply circuit, a resistance-varying member associated therewith, and means for operating said member, of regulator mechanism therefor comprising a plurality of electromagnets, and a mechanical connection therebetween whereby one of said electromagnets may act on said regulator mechanism to prevent hunting action.

17. A regulator system comprising means to be regulated, and regulator mechanism therefor comprising a plurality of connected electromagnets, one of said electromagnets being adapted to react upon said regulator mechanism to prevent hunting action in said system.

18. A regulator system comprising means to be regulated, regulator mechanism therefor comprising a plurality of electromagnets, and energy-transmitting means connecting said electromagnets, one of said electromagnets being adapted to react upon said regulator mechanism through said connection to prevent hunting action in said system.

In testimony whereof, I have hereunto subscribed my name this 12th day of Aug. 1919.

CLARENCE A. BODDIE.
